United States Patent

Des. 237,877
Patented Dec. 2, 1975

237,877

MOTOR AND GENERATOR EDUCATIONAL BOARD

Charles G. Valentine, Stamford, Conn., assignor to
Xerox Corporation, Stamford, Conn.

Filed Apr. 19, 1973, Ser. No. 352,799

Term of patent 14 years

Int. Cl. D19—07

U.S. Cl. D19—62

I claim:

FIG. 1 is a left perspective view of a motor and generator educational board showing my new design; and

FIG. 2 is a right perspective view thereof.

The rear of the motor and generator educational board not shown is plain and unornamented.

I claim:

The ornamental design of a motor and generator educational board, substantially as shown and described.
